(57) **CLAIM**

The ornamental design for a mountable sensor housing, as shown and described.

DESCRIPTION

FIG. 1 is a perspective view of the mountable sensor housing showing the new design.

FIG. 2 is another perspective view of the mountable sensor housing of FIG. 1.

FIG. 3 is a front view of the mountable sensor housing of FIG. 1.

FIG. 4 is a rear view of the mountable sensor housing of FIG. 1.

FIG. 5 is a side view of the mountable sensor housing of FIG. 1.

FIG. 6 is an opposing side view of the mountable sensor housing of FIG. 1.

FIG. 7 is a top view of the mountable sensor housing of FIG. 1; and,

FIG. 8 is a bottom view of the mountable sensor housing of FIG. 1.

1 Claim, 8 Drawing Sheets
